COMBINED BANK AND NIGHT LIGHT

Gerald I. Margolis, Highland Park, Ill., assignor to Colony Press, Inc., Chicago, Ill., a corporation of Illinois

Filed Jan. 23, 1961, Ser. No. 63,636

Term of patent 14 years

(Cl. D48—20)

FIG. 1 is a top perspective view of a combined bank and night light showing my new design; and
FIG. 2 is a bottom perspective view thereof.

The dominant features of my design for a combined night light and bank reside in the portions shown in full lines and said portions are characterized by the protruding panels on the side walls of the base as shown.

I claim:

The ornamental design for a combined bank and night light, as shown and described.
